JOSEPH GRISON, OF NEW YORK, N. Y.

AIR CONDITIONING DEVICE

Application filed September 6, 1932. Serial No. 631,787.

This invention relates to air conditioning devices, and more particularly to a portable device especially designed for cooling and cleansing air in dwellings, and relatively small enclosures, in contradistinction to the large air conditioning plants now used for conditioning air in theaters, auditoriums, and similar large enclosures.

As is well known, the common electric fan merely circulates the air and has no cooling effect. When the fan is stopped the air in the room is just as hot as it was before the fan was placed in operation. Consequently, the common electric fan has no cooling or dehydrating effect.

Air conditioning devices for small enclosures as have been heretofore provided, have necessitated electric motors, pumps, and refrigerating equipment to such an extent as to render their cost prohibitive. Also, cooling devices which employ large quantities of water ice over which air is blown by an electric fan are objectionable because of the cost of the ice, about 300 lbs. a day being needed; and because of the inconvenience in handling the large quantities of water resulting from the melting of the water ice. Also, the blowing of air over water ice causes an excessive amount of water in the air, which is undesirable and a source of discomfort.

It is, therefore, an object of this invention to provide a simple and inexpensive air conditioning device which requires no refrigerating equipment or large quantities of water ice.

A further object is the provision of an air conditioning device in which solidified carbon dioxide is used as the cooling medium, and water from the atmosphere is condensed on metal vanes chilled to a very low degree by the solidified carbon dioxide.

A further object is the provision of a simple, portable air conditioning device which requires very little attention, and which may be operated from the usual household electric light circuits.

A further object is the provision of an air conditioning device which may be conveniently moved from room to room; and which effectively distributes cool, dehydrated air to

all parts of a room by convection and by means of a blower which forces air over metal vanes chilled by a refrigerant such as solidified carbon dioxide, water ice, or the like.

A further object is the provision of an air conditioning device which has associated therewith a refrigerated compartment conveniently disposed and arranged for chilling beverages, foods and the like; or for use by physicians, pharmacists, photographers, etc., for chilling medicines, chemical compounds, etc.

These and other objects are attained by the novel construction, combination and arrangement of parts hereinafter described and shown in the accompanying drawings, constituting a material part of this disclosure, and in which:

Fig. 1 is a perspective view of the exterior 70 of the air conditioning device.

Fig. 2 is a longitudinal sectional view showing details of the interior of the device.

Fig. 3 is a transverse sectional view of the device.

Fig. 4 is a perspective view showing a refrigerant receiving chamber integrally attached thereto.

Referring to the drawings, the air conditioning device is shown to include a cabinet 80 having a removable front wall 5, side walls 6, a rear wall 7, and a removable cover 8, the cabinet being mounted upon casters 9 to enable to it be conveniently moved from room to room.

Positioned in the cabinet is a casing 10, preferably made of metal, said casing having a lower compartment 11 which is water tight so that it can safely hold condensed water received from the atmosphere.

The front of the casing is provided with an opening communicating with an air duct 12 integrally connected with the casing and upwardly directed, the mouth of the air duct registering with a plurality of spaced openings 13 in the front wall 5 of the cabinet.

The rear wall of the casing 10 has an opening 14 in which is positioned a fan 15 of the blower type, said fan being operated by an electric motor 16, the latter being mounted

upon a frame 17 supported by the side walls of the cabinet. The rear wall 7 of the cabinet has an opening 18 directly in the rear of the fan 15 so that air is drawn through the opening 18 by the fan 15 and forced through the casing 10 into the air duct 12. Mounted on the rear wall 7 is a speed control rheostat 19 which is conveniently controlled by a knob 20.

Mounted on the rear of the casing 10 and directly associated therewith is a metal compartment 21 in which is placed a coil 23 of metal tubing, said coil being integrally connected to an upwardly directed portion of tubing 22 and to a downwardly direction portion of tubing 24, the latter communicating with the chamber 11, for a purpose hereinafter explained.

Mounted in the casing 10 is a compartment 26 which is adapted to receive a block 27 of a refrigerant such as solid carbon dioxide or water ice. The compartment 26 is preferably made of a good heat conducting metal and communicates with a plurality of vertical chambers 28, said chambers being connected to a lower horizontal chamber 29, the side walls of the vertical chambers being corrugated.

The chambers 28 and the structure connected therewith are supported by angles 30 attached to the front and rear walls of the casing 10. Integrally attached to the metal chamber 26 are a plurality of vertical vanes 31, said vanes being corrugated and parallel to the side walls of the chambers 28.

The compartment 26 is provided with an aperture 32 through which carbon dioxide may escape as the block of carbon dioxide sublimes.

In operation, a block of solidified carbon dioxide or water ice is placed in the compartment 26, and the blower 15 is put in operation. The vanes 31 being in direct contact with the metal bottom of compartment 26, soon become chilled by conduction, and as air from the blower passes over the vanes, the air is chilled to a low degree of temperature. As there is a constant circulation of air through the blower and over the fans, it is readily seen that the temperature of a room will soon be reduced as the air itself is chilled, and not merely circulated as is the case when an ordinary electric fan is used. The chilled air is transmitted to all parts of a room by conduction and by the action of the blower.

When solidified carbon dioxide is used as the refrigerating medium, cold gas caused by the subliming of the block 27 of solid carbon dioxide diffuses downwardly in the chambers 28 and increases the chilling effect on the vanes. However, not all of the sublimed gas passes downwardly as an appreciable pressure is created in the compartment 26, and some of the gas is forced upwardly into the tube 22 and thence to the coil 23, to chill the compartment 21, the latter being also chilled

by conduction since it is in direct contact with the compartment 26. In this manner beverages, foods, chemicals, medicines, etc., may be effectively chilled and preserved in the compartment 21 without additional effort.

Preferably the walls of the compartment 21 are made of a good heat insulating material, and the compartment in practice should be provided with a substantially gas tight cover, also made of a heat insulating material.

It will be noted that the casing 10 and the air duct 12 prevent heat losses and that all of the air which is chilled by the vanes 31 and chambers 28 is blown through the air duct. As the vanes are chilled to a very low temperature, moisture in the atmosphere condenses thereon, and falls into the compartment 11 in the lower part of casing 10. The compartment 11 is preferably provided with a quantity of lime water the tube 24 communicates with compartment 11 so that the carbon dioxide gas exuding from the tube will be absorbed and neutralized by the lime water, or other carbon dioxide absorbing substances.

From the above description it will be seen that I have provided a simple and compact air conditioning device which may be economically operated with no inconvenience. The device may be readily moved from place to place, and when solidified carbon dioxide is used as the refrigerant, there are no waste products, such as water from melted water ice, to dispose of. The effect of the air conditioning device may be controlled by increasing or decreasing the action of the blower 15, by means of the rheostat 19 to regulate the speed of the blower fan.

It will also be noted that the arrangement of my compartment 26 with the chambers 28 and vanes 31 attached thereto presents a desirable device for use in household refrigerators with solid carbon dioxide as the refrigerant.

The foregoing disclosure is to be regarded as descriptive and illustrative only, and not as restrictive or limitative of the invention, of which obviously, an embodiment may be constructed including modifications without departing from the general scope herein indicated and denoted by the appended claims.

Having thus described my invention, what I claim as new and desire to secure by Letters Patent, is:

1. An air conditioning device, comprising a cabinet having a plurality of apertures in the front wall thereof and an opening in its rear wall, a casing mounted in the cabinet and having openings in its front and rear walls registering with the opening in the cabinet, an air duct attached to and communicating with the casing by means of the opening in the front wall of the casing, said air duct being upwardly directed and having its mouth in register with the apertures in the

cabinet, said casing having an upper compartment and a lower compartment, a plurality of vertical corrugated vanes suspended from the bottom of the upper compartment, said vanes being in alinement with the openings in the walls of the casing, a quantity of a refrigerant such as solidified carbon dioxide positioned in the upper compartment, and means for blowing a draft of air over said vanes.

10. 2. In an air conditioning device, a compartment having a bottom made of a good heat conducting material, said compartment being adapted to hold a quantity of a refrigerating substance, a plurality of vertical spaced chambers in communication with each other and with the compartment, the walls of said chambers being vertical and directly connected to the bottom of the compartment, and a plurality of vertical vanes directly connected to the bottom of the compartment, said vanes and the walls of the chambers being made of a good heat conducting material.

20. 3. In an air conditioning device, a casing having an opening in its rear wall, an air duct attached to the front wall of and communicating with the interior of the casing, a compartment mounted in the casing and having a bottom made of a good heat conducting material, said compartment holding a quantity of solidified carbon dioxide, a plurality of vertical metal corrugated vanes directly connected to the bottom of the compartment, means for blowing a draft of air over said vanes, a second compartment attached to the rear wall of the casing, and a coil of tubing positioned in said second compartment, said tubing communicating with the first compartment to receive cold 30 sublimed carbon dioxide gas to chill the second compartment so that the latter may be used for chilling beverages, foods and the like.

4. In an air conditioning device, a cabinet having apertures in the front wall thereof, a casing mounted in the cabinet, an upwardly directed air duct attached to and communicating with the casing and having its mouth in register with the apertures in the cabinet, a plurality of spaced vanes mounted in the casing, means for chilling said vanes to a low temperature, and means for blowing a draft of air over the vanes.

5. An air conditioning device, comprising a cabinet having a plurality of apertures in the front wall thereof and an opening in its rear wall, a casing mounted in the cabinet and having openings in its front and rear walls registering with the opening in the cabinet, an air duct attached to and communicating with the casing by means of the opening in the front wall of the casing, said air duct being upwardly directed and having its mouth in register with the apertures in the cabinet, said casing having an upper com-

partment and a lower compartment, a plurality of vanes suspended from the bottom of the upper compartment, said upper compartment being adapted to receive a quantity of a refrigerating substance, and means 70 for blowing a draft of air over said vanes.

JOSEPH GRISON.
